UNITED STATES PATENT OFFICE.

C. F. THEODOR STEINWAY, OF NEW YORK, N. Y.

DESIGN FOR A PIANO-FORTE CASE.

SPECIFICATION forming part of Design No. 11,856, dated July 6, 1880.

Application filed March 22, 1880. Term of patent 14 years.

To all whom it may concern:

Be it known that I, C. F. THEODOR STEINWAY, a citizen of the United States, residing in the city and State of New York, have invented and produced a new and original Design for Piano-Forte Cases, which is represented in the accompanying perspective view and described in the following specification.

It is the object of my invention to make the projecting arms which form the end walls of the key-board of an upright piano-forte harmonious elements in the general design of the case, and thus obtain a greater unity of effect than has heretofore been common in structures of this class.

The distinguishing feature of my design consists in the employment of insulated vertical columns, two of which support the key-board arms, respectively, and rest upon bases projecting forward from the lower front corners of the case, while two other vertical columns, erected, respectively, upon the key-board arms, support the cornice at the top of the case. There will thus be a peculiar boldness of effect and an incorporation of the key-board arms integrally into the general design, due to the presence of the vertical shafts, the one pair supporting the key-board arms and the other pair resting upon the key-board arms and supporting the cornice at the top of the case.

In the accompanying perspective view of a piano-forte embodying my design it will be seen that each of the lower columns, A, rests upon a base, B, projecting forward from one of the front corners, C, of the case, and at the top supports a console, D, upon which one of the key-board arms E rests. Each of the upper columns, F, rests upon a pier or base, F', erected upon the top of the key-board arm, and extending outward rather less than half the length of the arm, while the capital F² of the column supports the cornice G at the top of the case. The case may be paneled or ornamented on the ends and in front, as shown, or in any other desired manner; or the front may be made of fret-work, if desired.

I claim as my invention—

The design for an upright-piano-forte case herein shown and described, the same consisting of lower insulated vertical columns resting upon bases projecting forward from the front corners of the case, and supporting the key-board arms, respectively, and of the upper insulated columns, each resting upon one of the key-board arms and supporting the cornice at the top of the case.

C. F. THEODOR STEINWAY.
